UNITED STATES PATENT OFFICE.

HANS C. HANSEN, OF SEATTLE, WASHINGTON.

OVEN ATTACHMENT FOR STOVES.

1,327,203.

Specification of Letters Patent.

Patented Jan. 6, 1920.

Application filed January 18, 1918. Serial No. 212,521.

To all whom it may concern:

Be it known that I, HANS C. HANSEN, a citizen of the United States, residing at Seattle, in the county of King and State of Washington, have invented a new and useful Improvement in Oven Attachments for Stoves, of which the following is a specification.

This invention relates to improvements in attachments for cooking stoves, heaters, ranges and the like, and more particularly to the construction and method of heating the ovens of such stoves; and the object of this invention is to locate the position of the baking ovens in such relation to the fire box as to receive the full distribution of the upward rise of the heated air circulation over the sides of the ovens and thus eliminate the downward draft.

20 A further object resides in the manner of producing a more equal distribution of heat over all sides of the oven surfaces.

A still further object resides in conservation of fuel due to an unimpaired draft, which precludes the temperature of the ovens from cooling off. To maintain the ovens at approximately normal baking temperature the heat must circulate freely thereover. In stoves, where the ovens are to the side or below the fire box, the heated air must be drawn downwardly in order to pass around the sides of the ovens. This condition requires a good size fire to create sufficient draft to force the heat below. The physical law of heat is to rise. It can be readily seen that unless a good size fire is maintained in the fire box there cannot be sufficient draft created to force the heat downwardly, and consequently without draft there is not the oxygen drawn into the fire box to support combustion, the heat value of the fuel is lost in smoke, which escapes up the chimney, and the fire soon becomes extinguished unless revived.

45 Further advantages will appear from the following specification, illustrated in the accompanying drawings, and finally pointed out in the appended claims.

In the drawings, Figure 1 is a front elevation of an ordinary stove, showing the ovens as applied thereto; Fig. 2 is a plan view of the ovens illustrating the direction of air circulation thereunder; Fig. 3 is a sectional view taken along line 3—3 of Fig. 2; and Fig.

4 is a side elevation of an oven that can be attached to an ordinary range or heater.

Referring more particularly to the drawings, in which like numerals indicate like parts, the numeral 1 represents an ordinary range and 2 indicates the main pipe that leads to the pipe exit 20. 3 are the improved baking ovens which are located in substantially the same position on a range as the usual warming ovens thereof, and 3' are the doors that are hingedly secured in any well known manner.

I have herein shown the ovens in pairs instead of singly with a partition wall 4 therebetween. 5, 6 and 7 indicate the bottom, sides and upper passageways respectively for the heated air circulation between the ovens and the outer casing 8.

For the purpose of insuring a more equal distribution of heat over the entire area of the oven surfaces, I have employed a plurality of deflectors 9, as shown in Fig. 3, radiating from the main pipe 2 to the sides of the ovens. These deflectors are preferably semi-circular with an exposed upper side which is adapted to come flush with the bottom plate of the ovens. This construction causes the heat circulation to be concentrated in units and is drawn through these apertures along the exposed bottom surface of the oven and passes out into the channel 6 and thence upwardly along the sides of the ovens and over the top thereof.

11 is a horizontal deflector plate that is provided between the ovens and the outer casing 8 and terminates short of the outer casing to the rear thereof to form an outlet 13. This plate deflects the heat along the sides of the ovens and the outlet 13 permits the heat circulation to rise upwardly into the passageway 7 and thereby heat the top of the ovens in its final course to the exit pipe 20. It is to be observed that the passage of heated air circulation is only deflected horizontally and is never caused to be directed downwardly, hence the draft is not impaired.

14 indicates a door provided on the bottom side of the ovens, whereby the deflectors 9 as a unit can be withdrawn and the soot removed therefrom, and 15 and 16 are similar doors to permit the removal of soot from the deflector plate 11 and from the passageway 7 respectively.

This oven improvement can be easily attached to any range or heating stove, or formed integral therewith. A damper 17 provided on the exit pipe 20 provides a shut-off or direct draft up the chimney for starting the fire burning at the beginning. A damper can likewise be provided on the range 1 to shut off the circulation from the original ovens and utilize the heat radiation 10 for warming purposes only, if desired.

It is obvious that various mechanical changes can be made in the manner of construction within the scope of the appended claims.

15 What I claim is new, and desire to protect by Letters Patent, is:

1. In combination with a stove and stove pipe, an oven provided above the fire box of said stove, a casing spaced apart from 20 said oven providing a passageway for the circulation of heated air around all sides of said oven, a series of deflectors provided beneath said ovens in said passageway connecting radially with said pipe, and deflectors on the sides of said oven in said 25 passageway for diffusing the heat circulation horizontally over the sides of said oven.

2. A range comprising an oven provided above the fire box thereof, an outer casing spaced apart from said oven providing a 30 passageway for the circulation of heated air around all sides of said oven, a stove pipe leading from said fire box upwardly and connecting with said passageway, a series 35 of deflectors provided in the bottom of said passageway and adapted to engage said

pipe and form a plurality of circulation chambers beneath the bottom surface of said oven for diffusing heat thereunder.

3. A range comprising an oven provided 40 above the fire box thereof, an outer casing spaced apart from said oven providing a passageway for the circulation of heated air around all sides of said oven, a stove pipe leading from said fire box upwardly and 45 connecting with said passageway, a series of deflectors provided in the bottom of said passageway and adapted to engage said pipe and form a plurality of circulating chambers beneath the bottom surface of 50 said oven, and a horizontal deflector provided in said passageway on the side of said oven for diffusing heat flowing from said chambers.

4. An oven attachment in combination 55 with a stove and the stove pipe, an outer casing spaced apart from said oven providing a passageway for the circulation of heated air around all sides of said oven, deflectors adapted to articulate with said pipe 60 within the bottom of said passageway, a deflector on the sides of said passageway for diffusing the circulation of heat horizontally and means for disengaging said deflectors for removing the accumulation of 65 soot.

Signed by me at Seattle, Washington, this 30 day of December, 1917.

HANS C. HANSEN.
